UNITED STATES PATENT OFFICE.

CHARLES J. VAN DEPOELE, OF CHICAGO, ILLINOIS.

ELECTRIC SAFETY CUT-OUT.

SPECIFICATION forming part of Letters Patent No. 291,649, dated January 8, 1884.

Application filed April 21, 1883. (No model.)

To all whom it may concern:

Be it known that I, CHARLES J. VAN DEPOELE, of Chicago, in the county of Cook and State of Illinois, have invented new and useful Improvements in Safety Cut-Outs for Electric Lamps, (by induced current;) and I do hereby declare that the following is a full, clear, and exact description thereof, reference being had to the accompanying drawings, which form a part of this specification.

My invention relates to a new and useful attachment to electric lamps; and it consists of an arrangement by means of which, in a series of lamps, in case of an abnormal elongation of the arc in such lamp, said lamp shall be automatically cut out of circuit, thus preventing the other lamps in circuit being extinguished by the breaking of the circuit in the faulty lamp. This I accomplish in a novel way, not by a derivation between the carbon-points, as is generally done, but by an induced current; not in circuit with the general circuit or a shunt therefrom, but by an induced current obtained from the vibrating electro-magnet, which I employ in connection with the feed mechanism of the lamp.

The following is a clear explanation of the principle upon which the invention is based, and how brought to operate, reference being had to the annexed drawings, forming part of my specification.

Figure 1 shows a front elevation of the electric-arc lamp, with the automatic arrangement attached to the same. A and B are the electro-magnets working the mechanism of the feed A, which is provided with two separate helices, A' A'', that form the primary and secondary circuits of an induction-coil, one of said circuits (preferably A') being traversed by a pulsating current in a derivation from the main circuit, such as patented by me, No. 262,333, August 8, 1882; No. 257,989, May 16, 1882; No. 261,280, July 18, 1882, and as used in all my lamps at present. This circuit in this instance is as follows: The inner end of coil A' is, by a proper conductor, 9, connected to the negative pole of lamp at 7, while the outer end of same coil is connected by a wire, 10, to an insulated contact-screw, I, from whence it passes to spring-contact S', which is in connection, through the vibrator and all the metallic parts of top of lamp, with the positive

pole. The second coil, A'', around this electro-magnet is entirely independent of and insulated from the former circuit. The terminals 55 O' O'' are leading-wires transmitting an induced current from coil A'', produced by the interruption or vibration of coil A', to an automatic cut-out of any suitable description, two kinds of which are shown in the drawings at 60 Figs. 1 and 3. B is the electro-magnet in the main circuit. C is a small electro-magnet intended to release the detent D upon E. E is a contact insulated from the rest of the lamp-frame, and electrically connected to negative 65 binding-post N by screw F, by suitable conductor, 7. P and N are the positive and negative binding posts.

Fig. 2 is a side view of electro-magnet A, provided with contact breaker or vibrator, 70 such as described in an application now pending on electric-arc lamps. The current in this electro-magnet is taken between the positive and negative binding-posts of the lamp, being thus a derivation from the main current. 75 The electro-magnet A has two separate and independent windings, A' A'', around its core—one, A', in a derivation, as above said, from the main circuit. The second coil, A'', is thoroughly insulated from the latter circuit, and 80 is intended to produce a current induced by the intermittent and pulsatory current in the primary coil A', which induced current will be proportional to the current present in A' when the same is made and broken. The current thus produced is intended to operate the detent D, and to cut out of circuit the lamp or carbons, in case the latter fail to feed. 85 O' and O'' are the two terminals of the induced-current coil. The coil A'' can be made either 90 with fine or coarse wire, so as to produce a current of high or low potential, as may be needed.

Fig. 3 is a front elevation of the electric-arc lamp, in which the automatic arrangement is not operated, as in Fig. 1, by an electro-magnet, C, but by a platinum or other metallic wire, C', expanded by the heat produced in said wire by the passage of the induced current from A''. When the wire C' expands, the 95 catch C'' responds to the action of a spring, S, thus releasing the detent D upon E and cutting the light-circuit out of operation. The detent D is of considerable size, and, being in

electrical connection with the frame and all positive parts of the lamp, when liberated, completes a short circuit, including the frame of the lamp, and of ample capacity to carry the whole current. O' and O'' are connecting-wires to C' from coil A' . Normally the current enters positive binding-post, passes over to carbon at 2, to lower carbon, and by suitable conductor, at 3, to insulated screw 4, up to 5, into coil of B , out at 6 to 7, thence to 8, which is in connection with negative binding-post of lamp. The insulation is further indicated in black. The rheotome necessary to the operation of and omitted from Fig. 3 is clearly shown in Fig. 1, and also separately in Fig. 2.

Having described the different parts of my invention, I will now explain the same when in operation.

My aim has been in this device to produce an arrangement requiring no closed derived circuit to operate the automatic cut-out of a lamp. It often happens that, for some cause or other, the automatic arrangement depending upon a derivation from the main circuit does not come into operation in time, and thus burns out the fine wire placed in such derivation, which has to be replaced in order to make the lamp work again, whereas in my system of employing a pulsatory derived circuit instead of a continuous one I run no risk of burning out the fine wire in my lamps; and, moreover, I am enabled to generate a current which, although not being common either with the main or derived circuit, and having no electrical connections with either, will be able to operate an automatic arrangement or device for cutting a faulty lamp out of circuit, or complete the circuit when it is open between two carbons in a lamp.

As above stated, the electro-magnet A is wound with two separate helices, A' and A'' . A' is in a derivation from the main circuit between the two poles of the lamp, the current in which helix is constantly made and broken. The second helix, A'' , is perfectly insulated from the former circuit, and it emits a current that is induced by the pulsating or intermittent current in A' , so that whenever the current in A' is weak very little current will be generated in A'' ; but, on the contrary, when the current in A' increases, so will the current in A'' , which is made to work the automatic device above referred to.

Fig. 1 shows the arrangement operated by an electro-magnet, C , excited by the induced current of A'' . Although the current in A'' is alternating, by giving the right proportions to electro-magnet C , it will be sufficiently energized to enable it to raise its armature C' and liberate the detent D . However, if it is desirable, the electro-magnet C can be replaced by a fine platinum wire, which will ex-

pand on the passage of the current produced in A'' , and so operate the cut-out, as shown in Fig. 2. The current in A'' will rise and fall with the current in A' , so that whenever A' receives more than its normal current the current in A'' will also increase correspondingly, and thus be made to operate the devices above explained and described.

I do not limit myself to the above method of producing the induced current in the coils of A'' . Any other disposition of the pulsating shunt-current can be adapted to develop an induced current in an independent helix, and this current applied to operate a circuit-closer.

What I claim as new, and desire to secure by Letters Patent, is—

1. In an electric-arc lamp, an electro-magnet located in a derivation between the carbons, and provided with a vibrating circuit-breaker operating to produce a pulsating current in the coils of said electro-magnet, in combination with a secondary helix wound thereon, but not electrically connected to the same, and connections, substantially such as described, whereby the induced current operates a safety cut-out for electric-arc lamps, as described and specified.

2. In an electric-arc lamp, a coil in which an induced current is produced by the pulsations or interruptions in an electro-magnet, the coils of which are in a derivation between the two carbons in the lamp, and which is provided with vibrating circuit-breaking devices, said induced current being adapted to operate a circuit-closer in said lamp, as described and specified.

3. In an electric-arc lamp, an electro-magnet wound with two helices, one of said helices being in derived circuit, and provided with a rheotome adapted to produce therein a pulsating derived current, the other helix being well insulated from the former, and adapted to emit a secondary current under the influence of the pulsating derived current, and by means of devices, substantially such as described, to work a circuit-closer, as described, and for the purposes set forth.

4. In an electric-arc lamp, the contact-piece E , well insulated from the metallic parts of the lamp, and properly connected to the negative binding-post thereof, in combination with the detent D , held in place by catch C' , the expanding wire C' , and insulated eye G , all operated by the secondary current produced in a coil wound on the shunt electro-magnet of the lamp, as above described, and for the purpose set forth.

CHARLES J. VAN DEPOELE.
